UNITED STATES PATENT OFFICE

128,612

DESIGN FOR A GAME BOARD

John H. Beck, Kansas City, Mo.

Application May 24, 1941, Serial No. 101,121

Term of patent 14 years

To all whom it may concern:

Be it known that I, John H. Beck, a citizen of the United States, residing at Kansas City, in the county of Jackson and State of Missouri, have invented a new, original, and ornamental Design for a Game Board, of which the following is a specification, reference being had to the accompanying drawing, forming a part thereof.

Fig. 1 is a plan view of a game board showing my new design.

Fig. 2 is an edge view of said game board.

I claim:

The ornamental design for a game board, as shown.

JOHN H. BECK.
